KNITTING NEEDLE LATCH

Charles L. Page, Philadelphia, Pa.

Application April 10, 1940, Serial No. 328,942

4 Claims. (Cl. 66—121)

The present invention relates to improvements in knitting needle latches, and more particularly relates to the structure of the spoon which cooperates with the hook of the needle.

Heretofore the standard spoon is formed with a rather shallow depression which is intended to close upon the hook of the needle, but, due to variations in manufacture and other causes, this ideal condition is often prevented in practice by the rim of the depression which lies at the extremity or free tip of the spoon, this part of the rim often encountering the rounded part of the hook and interfering with that final ideal seating of the depression over and upon the hook.

As the result of this imperfect mating between spoon and hook, the latch is very often thrown laterally out of alignment, as by knots or slubs in the yarn, to such an extent that there is such a misalignment of spoon and hook as to cause the spoon to be pushed to one side of the hook. This condition is attended by a distortion or bending of the latch and often results in breakage at its weakest point which lies in the zone between the spoon and the blade. The loss and expense of the latch is not the only difficulty because of this failure in practice because the yarn and the fabric often both suffer when such a failure occurs.

It is a primary object of the present invention to overcome the above enumerated difficulties and to this end the invention proposes to provide a novel form of spoon in which the rim tip of the depression is dispensed with, allowing free and full closing of the depression upon the hook, in deepening the walls of the spoon at the sides of the depression and in changing the angle at which the outer portions of these walls engage the sides of the hook to present inner wall surfaces more fully overlapping the hook and which will more effectively prevent any sidewise or lateral moving of the latch with respect to the hook.

The invention also contemplates the reinforcement of the latch at certain critical points occasioned by the new formation given the latch in the particulars noted in the preceding paragraph.

The invention also aims to correct the prior maladjustment of parts and the difficulties incident thereto by simple rearrangement of latch parts without entailing any radical changes in the latch which would demand new manufacturing equipment or a new form of needle.

With the foregoing and other objects in view the invention will be more fully described here-

inafter and more particularly pointed out in the subjoined claims.

In the drawing, in which like parts are denoted by the same reference characters throughout the several views,

Figure 1 is a partial side view of a knitting needle showing the improved latch in the closed position.

Figure 2 is a similar view with the latch open.

Figure 3 is a top plan view of the improved latch.

Figure 4 is a side elevation of the same.

Figure 5 is a side view with parts broken away and shown in longitudinal section along the line 15 5—5 in Figure 3.

Figure 6 is a cross sectional view on an enlarged scale taken on the line 6—6 in Figure 4, and

Figure 7 is a perspective view of the improved latch.

Referring more particularly to the drawing 10 designates the shank of a conventional knitting needle in which the cheek is indicated at 11 and the hook at 12. The usual slot 13 is formed 25 in the cheek and shank and is adapted to receive the blade 14 of the latch which is pivoted in the slot 13 of the cheek 11 in the customary manner as by the rivet 15. The blade 14 carries a spoon 16 which, together with the blade, is the subject 30 of the present invention.

I first propose to eliminate the rim which lies at the free tip of the spoon so that the depression 17 is free, unimpeded and open at this point being bounded only by the bottom wall 18, where- 35 by this bottom wall 18 may move toward and from the hook 12 and the bottom wall 18 of the latch may always seek, without interference, the hook 12.

The side walls 19 of the spoon are made of a 40 greater depth in comparison with the standard side walls, the overall depth of the spoon being in excess of that of the depth of the standard spoon. Moreover these side walls are substan-

tially parallel and then run straight or substan-

45 tially straight down the sides of the depression in substantial parallelism with the longitudinal center line of the latch from the open end of the spoon to points near the inner closed end of the depression 17 where such side walls 19 gradually converge together and into the body of the spoon

50 16. The side walls 19 moreover have substan-

tially flat inner faces 20 which are parallel to one another like the legs of a U. In other words viewing the depression in the cross sectional aspect the form is U-shaped as shown in Figure 6.

As shown in Figures 4 and 5 the outer edges of the side walls or wings 19 gradually slope downwardly as indicated at 21 toward the bottom wall 18. The top edges 22 of the side walls or wings 19 are tapered outwardly and downwardly from the upper edges of the flat inner faces 20 to the outer sides 23 of the spoon. The formation of the side walls 19 deeper over standard practice gives rise to a further problem in the open position of the latch in that this deeper wall portion 19 would ordinarily stand out from the shank 10 a greater distance than normal which would result in straining the stitches as the needle moved up through the fabric. To counteract this tendency I remove portions of the bottom wall of the spoon adjacent the blade 14, such removed portions being indicated at 24 so that the thin cross section of the blade 14 along the bottom of the blade and for a distance into the bottom portion of the spoon is continued to constitute a thin spoon bottom portion 25. Otherwise stated blade 14 is continued into the spoon; or the bottom walls of the spoon represented at 26 have been raised preferably along the sloping line as shown in Figure 4.

It will be noted that the removed portions 25 of the bottom of the spoon at opposite sides of the blade 14 are counteracted in any weakening tendency by virtue of additional bodies of material 27 added between the spoon and the upper side portions of the blade 14, which material is the usual material out of which the latches are made. The bottom sloping walls 26 also define the lower limit of these additional bodies of material 27 which serve to reinforce and strengthen the latch at the aforesaid weakest part between the spoon and blade and particularly overlapping the removed portions 25 at the bottom part of the spoon.

Figure 3 shows in top plan view the open tip edge of the depression 17 as well as the straight character of the inner faces 20 of the side walls or wings and also the large bodies 27 of additional reinforcing material at the inner edge of the spoon and of the gently sloping external boundary lines 28 of these bodies which gently slope into the sides of the thin portion of the blade 14.

Figure 4 shows how the bottom edges of the reinforcing bodies 27 are undercut on the sloping line 28 at opposite sides of the blade 14, thus permitting the blade to continue into and under the spoon but at the same time reinforcing this blade and the spoon above the portion where the removed portions 24 have been withdrawn.

Figures 1 and 2 show the two positions of the latch. In Figure 1 the spoon is shown closed against the hook 12, indicating that the open tip of the depression permits the bottom wall 18 to at all times seek a position flat against the end of the hook 12. In this figure also the deep side walls 19 are shown as extending well beyond the center line of the hook 12 in which position it would be difficult for any sidewise motion imposed on the latch to enable the spoon to disengage the hook. Moreover the depth of the side walls 19 causes the leading edges 21 and 22 of the side walls to overlap the sides of hook 12 at an earlier point in the rotational closing movement of the latch, which is also efficacious in tending to avoid lateral torsional movement of the latch out of alinement with the hook 12 in the closing action of the spoon upon the hook. Moreover the presence of the reinforcing bodies 27 which extend along the blade 14 to a greater

5 extent than any part of the spoon in the standard construction tends to reinforce the blade against any bending stresses, at least to a further point along its length toward its pivot 15 than has been the practice heretofore.

10 As shown in Figure 6, the flat side faces 28 engage the sides of the hook 12. These side faces 20 are therefore at right angles to any strain or any force acting laterally tending to distort the latch out of its mating alinement with the hook 12.

15 After the needle has drawn the stitch and is again rising on the side cam the latch is opening, that is descending, and inasmuch as such latch may have any tendency to get across the sinkers, the tapering bottom walls 26 will engage the sinkers and exert a gentle tendency on the latch to return to its normal vertical path of movement between adjacent sinkers; and in this way the walls 26 cooperate with the sinkers in maintaining correct alinement and operation of the latches.

20 The language used in the claims refers to the invention when in the position illustrated in Figure 1.

25 It is obvious that various changes and modifications may be made in the details of construction and design of the above specifically described embodiment of this invention without departing from the spirit thereof, such changes and modifications being restricted only by the scope of the following claims.

What is claimed is:

1. In combination with a knitting needle having a hook and a slotted cheek, an improved latch comprising a blade and a spoon, said blade pivoted to the needle cheek within said slot, said spoon having a depression adapted to receive said needle hook in the upper closed position of the latch, said spoon having deep side walls at the sides of said depression for flanking the sides of the needle hook and appreciably overlapping the end of the needle hook, the tip end of said depression being open and unimpeded to permit said needle hook to engage the bottom of said depression, the upper line of said blade and spoon walls being substantially coincident, additional bodies of material on the sides of said blade adjoining and merging with the portions of the spoon side walls adjacent said upper line, the material below said bodies and below the adjacent portion of the spoon being removed at opposite sides of said blade to permit the blade to enter the slot in the needle cheek down to a low point on the spoon to compensate for the increase in the height of said side walls, the undersides of said additional bodies and of said walls being tapered lengthwise of the blade and spoon and at the same time rounded transversely to coact with adjacent sinkers in the downward swinging motion of the latch to preserve the center alinement of the latch.

2. In combination with a knitting needle having a hook and a slotted cheek, an improved latch comprising a blade and a spoon, said blade pivoted to the needle cheek within said slot, said spoon having a depression adapted to receive said needle hook in the upper closed position of the latch, said spoon having deep side walls at the sides of said depression for flanking the sides of the needle hook and appreciably overlapping the end of the needle hook, the upper line of said blade and spoon walls being substantially coincident, additional bodies of material on the sides of said blade adjoining and merging with the

portions of the spoon side walls adjacent said upper line, the material below said bodies and below the adjacent portion of the spoon being removed at opposite sides of said blade to permit the blade to enter the slot in the needle cheek down to a low point on the spoon to compensate for the increase in the height of said side walls, the undersides of said additional bodies and of said walls being tapered lengthwise of the blade and spoon and at the same time rounded transversely to coact with adjacent sinkers in the downward swinging motion of the latch to preserve the center alinement of the latch.

3. In combination with a knitting needle having a hook and a slotted cheek, an improved latch comprising a blade and a spoon, said blade pivoted to the needle cheek within said slot, said spoon having a depression adapted to receive said needle hook in the upper closed position of the latch, said spoon having deep side walls at the sides of said depression for flanking the sides of the needle hook and appreciably overlapping the end of the needle hook, said side walls terminating short of the tip end of the spoon and being separated and spaced apart to provide an open tip end with a projecting bottom portion, the upper line of said blade and spoon walls being substantially coincident, additional bodies of material on the sides of said blade adjoining and merging with the portions of the 30

spoon side walls adjacent said upper line, the material below said bodies and below the adjacent portion of the spoon being removed at opposite sides of said blade to permit the blade to enter the slot in the needle cheek down to a low point on the spoon to compensate for the increase in the height of said side walls, the undersides of said additional bodies and of said walls being tapered lengthwise of the blade and spoon and at the same time rounded transversely to coact with adjacent sinkers in the downward swinging motion of the latch to preserve the center alinement of the latch.

4. In combination with a knitting needle having a hook and a slotted cheek, an improved latch comprising a blade and a spoon, said blade pivoted to the needle cheek within said slot, said spoon having a depression adapted to receive said needle hook in the upper closed position of the latch, additional bodies of material on the sides of said blade adjoining and merging with the portions of the spoon adjacent the upper part only of the spoon, the undersides of said additional bodies and said spoon being tapered lengthwise of the blade and spoon and at the same time rounded transversely to coact with adjacent sinkers in the downward swinging motion of the latch to preserve the center alinement of the latch.
